UNITED STATES PATENT OFFICE.

SOTERO L. ZAMBRANO, OF NEW YORK, N. Y.

DESIGN FOR A DIPLOMA.

51,035.

Specification for Design. Patented July 10, 1917.

Application filed January 19, 1916. Serial No. 73,075. Term of patent 14 years.

To all whom it may concern:

Be it known that I, SOTERO L. ZAMBRANO, a citizen of the Republic of Mexico, residing at New York, in the county of New York and State of New York, have invented a new, original, and ornamental Design for Diplomas, of which the following is a specification, reference being had to the accompanying drawing, forming part thereof.

The figure is a plan view of a diploma illustrating my new design.

I claim:

The ornamental design for a diploma, as shown.

SOTERO L. ZAMBRANO.

Witnesses:

FREDERICK H. MILLER,
H. GLINTMORE.
